[57] CLAIM

The ornamental design for a tongue brush head and handle unit, as shown and described.

DESCRIPTION

FIG. 1 is a perspective view of a tongue brush head and handle unit showing my new design;

FIG. 2 is a right side elevational view thereof, the left side being a mirror image;

FIG. 3 is a front elevational view thereof;

FIG. 4 is a rear elevational view thereof;

FIG. 5 is a bottom plan view thereof; and,

FIG. 6 is a top plan view thereof.

The broken lines showing of bristles in FIGS. 2 and 3 are for illustrative purposes only and form no part of the claimed design.
